CLAIM

The ornamental design for a general purpose engine, as shown and described.

DESCRIPTION

FIG. 1 is a front view of a general purpose engine showing my new design;

FIG. 2 is a side view thereof;

FIG. 3 is another side view thereof;

FIG. 4 is a rear view thereof;

FIG. 5 is a top view thereof;

FIG. 6 is a bottom view thereof;

FIG. 7 is a perspective view thereof;

FIG. 8 is another perspective view thereof; and,

FIG. 9 is another perspective view thereof.

The broken lines in the Figures are for illustrative purposes only and form no part of the claimed design.
